UNITED STATES PATENT OFFICE.

CARL P. NACHOD, OF PHILADELPHIA, PENNSYLVANIA.

SIGNALING SYSTEM FOR HIGH-VOLTAGE RAILWAYS.

1,111,851.

Specification of Letters Patent. Patented Sept. 29, 1914.

Application filed July 23, 1912. Serial No. 711,023.

To all whom it may concern:

Be it known that I, CARL P. NACHOD, a citizen of the United States, residing in the city of Philadelphia, county of Philadelphia, and State of Pennsylvania, have invented a new and useful Signaling System for High-Voltage Railways, of which the following is a specification.

My invention relates to a signaling system for use in connection with an electric railway, particularly when the latter employs current delivered to it at high voltage.

It is the object of my invention to apply to an electric railway system a signaling system whose motive devices, electro-magnets, etc., shall be subjected to a voltage less than the voltage of the electric railway system; and whose conductors, magnet windings, etc., shall be maintained, by a source of electro-motive-force, at a potential higher than earth or the return circuit or path for the power current, whereby, among other things, the signaling system as a whole is independent of conditions in the return or earth connection of the power system; and in carrying out my invention I prefer to resort to apparatus and arrangements which shall cause a minimum of or substantially no waste of energy in the signaling system, notwithstanding its coöperation with the electric railway system of higher voltage.

The power consumption for an electric railway is relatively high, due to the fact that heavy cars or trains must be moved; and when the power must be transmitted a long distance, as when the electric railway is of unusual length, as for example, an inter-urban railway, economy is effected by raising the voltage on the feeders and contact conductors or trolley wires. The standard practice for a long time has been to employ a pressure of 500 volts, or thereabout, and more recently railways have been equipped to operate on a line voltage of 1200 volts, or 1500 volts, more or less. To apply signaling apparatus to be subjected to such high voltages requires that the magnet windings of the signaling apparatus, and other windings, shall be of very fine wire, which is very costly and which requires greater winding space, because of greater proportion of space occupied by insulation and because such insulation must

be heavier for the higher voltages, to accomplish the same results and which is far more liable to derangement and over-heating. In other words to adapt signaling apparatus to a high voltage system involves greater expense and greater size of the signaling apparatus without accomplishing any better or improved results. And the employment of resistances in the circuits of the windings of the signaling apparatus involves unnecessary waste of energy. By my invention however I subject the signaling apparatus to a lower voltage than the voltage of the electric railway system, particularly when the voltage of the electric railway system is 1200 or 1500 volts, more or less, though it is to be understood that my invention is equally applicable to a 500 volt electric railway system, or an electric railway system of any other voltage.

My invention resides in the features hereinafter described and claimed.

For an illustration of some of the forms my invention may take reference is to be had to the accompanying drawings, in which:

Figure 1 is a diagrammatic view of circuits and apparatus illustrating one form of my invention. Fig. 2 is a fragmentary diagram illustrating another method of providing a lower voltage for the operation of the signaling system. Fig. 3 is a fragmentary diagram showing a further method of securing a lower voltage for the signaling system operation. Fig. 4 is a fragmentary diagram illustrating a further method of securing a lower voltage for operation of the signaling system. Fig. 5 is a view illustrating the means for operating the revolving switch employed in the system illustrated in Fig. 1. Fig. 6 is a view illustrating the control of signal disks or semaphores. Fig. 7 is a fragmentary diagrammatic view of means for maintaining lower voltage on the signaling system.

Referring to Fig. 1, G and G¹ represent two generators connected in series with each other between the feeder conductor f and the ground or rail return g of an electric railway system. Or G and G¹ may represent the direct current sides of two rotary transformers supplying current for the operation of an electric railway system, or a section thereof. The contact conductor or trolley

wire of the electric railway system is represented at 1 with which connections are made to the feeder f at a plurality of points, as indicated for example at a , a . By way of example merely I have shown a signaling system associated with a single track block of an electric railway system. It is to be understood however that my invention is not limited in this regard but that it is applicable 10 in other relations to electric railway systems of any number of tracks. And it is to be understood further that my invention is not restricted to the particular signaling system described, for it is within my invention 15 to employ any other suitable signaling system.

The contact conductor 1 is here illustrated as extending throughout a block at whose ends are the turnouts or sidings beginning 20 at the points 2 and 3. At the turn-out 2 is located the signaling apparatus X and at the turn-out 3 is located the signaling apparatus Y .

Similar parts at station Y are designated 25 by characters similar to those at station X but with the addition of prime marks.

At station X the control contactor comprises the contacts 4 and 5 disposed longitudinally of and in proximity to conductor 30 1. They are insulated from each other and engaged in succession by the traveling contact, such as a trolley wheel, carried by a railway vehicle or train, such traveling contact or trolley wheel being indicated at station Y at z . When the traveling contact engages either contact 4 or contact 5 it brings it into electrical connection with the conductor 1.

The contact 4 is connected by conductor 6 40 with the armature 7 of relay F and contact 5 connects by conductor 8 with the armature 9 of relay E . The armatures 7 and 9 normally rest against the back contacts 10 and 11 and when attracted engage the front contacts 12 and 13. Contacts 10 and 13 are connected to each other and contacts 9 and 12 are connected to each other. One terminal of the winding of relay F is connected to contacts 12 and 9, and, similarly, one terminal of the winding of relay E is connected to contacts 13 and 7. The other terminal of the winding of relay F connects by conductor 14 with one terminal of the electro-magnet C whose other terminal connects 50 through conductor 15 with the conductor K constitute the return conductor of the signaling system, such conductor K being at a substantial voltage above the ground or rail return g and connected at 16 between the two generators or sources G and G' . The remaining terminal of the winding of relay E connects through conductor 17 with one terminal of electro-magnet A whose other terminal connects with the conductor K 65 through conductor 18.

When a car or vehicle passes from left to right under contacts 4 and 5, contact 4 is first brought into connection with the conductor 1, by the traveling contact, and accordingly current flows from contact 4 through conductor 6, armature 7, contacts 10 and 13, relay E , conductor 17, electro-magnet A , to conductor K . Accordingly electro-magnet E is energized attracting armature 9 away from contact 11 and into engagement with contact 13. When the contact 5 is reached by the traveling contact, current flows through conductor 8, armature 9, contact 13, electro-magnet E , electro-magnet A to conductor K , thus retaining the 80 connections the same as when contact 4 was in circuit. Since the connections are exactly symmetrical for relay F , a car running in opposite direction first makes circuit through contact 5 which energizes relay F , 85 which is maintained energized when the traveling contact reaches contact 4. When the traveling contact has passed, the armature 9 or 7, which was attracted, falls to the normal position indicated.

When the signals are in neutral position, as illustrated, that is, not giving an indication, there is a circuit from conductor 1 through conductor 19, contact 20, conductor 21, switch 22, 23, contact 24, contact 25, conductor 26, conductor 27, through magnet H' to the signal return conductor K .

A car entering the block from the turnout 2, from left to right, causes, due to the connection of relay E , a current to flow through the magnet A to the conductor K to the other terminal of the generator G , to whose voltage only the signal system is subjected. The energization of magnet A causes the dog 31, Fig. 5, to step the notched wheel 32 around one notch thereby rotating the shaft 33 so that the contact 22 breaks circuit with contact 23, thus breaking the circuit of the magnet H' which is accordingly deenergized, thereby releasing its armature, and accordingly the red disk signal, the stop signal R' , is moved by gravity, see Fig. 6, to indicating position indicated by the dotted circle 34'. When this occurs contacts 35' and 36' are bridged by 37', and current accordingly flows through conductor 19', contact 36', member 37', contact 35', through red lamp r' to the return conductor K , causing the red lamp r' to glow and give a red or stop signal corresponding with the red disk R' . Current also flows simultaneously through conductor 19', contact 36', member 37', and the interlock signal wire 39', 39, through contacts 40 and 41, controlled by magnet H thence through switch 42, 43, which is closed due to the aforementioned rotation of shaft 33, thence through contacts 44, 45, magnet D to conductor K . Coil D is accordingly energized, attracts its armature, and allows the white disk W to be 130

operated by gravity, see Fig. 6, to move to indicating position 34. In moving to indicating position the white signal W closes circuit between conductor 19 and contact 48 thereby allowing current to flow from conductor 1, through conductor 19, contact 48, white light w, to conductor K.

Every impulse of current through magnet A rotates the revolving switch, shown in Fig. 5, one notch in clockwise direction, and every impulse of current in coil C, as a result of a car leaving the block to the turnout 2, from right to left, rotates the revolving switch one notch in counter clockwise direction. Therefore after all cars entering the block have left the block the signals will again resume their neutral positions. When a car goes completely through the block from left to right it will set a white or permissive signal at the entering end and stop or red at the leaving end.

The above is the general operation of the signaling system illustrated. While it has further features of advantage and operation, the same are not pertinent to the present invention and are therefore omitted.

It is apparent from the foregoing description that the magnets and windings of the signaling system are not subject to the difference of potential between the trolley wire 1 and the earth or rail g, but to a potential less than the electric railway potential, with the result that there is far less danger to the signaling apparatus, both as to heating, sparking, break down of insulation, etc., and furthermore it will be less liable to derangement and will be smaller and less expensive than if required to operate on the full voltage in the electric railway system, and will operate economically as to the consumption of power. For example the generators or sources G and G¹ may each produce a pressure of 600 volts, whereby there is a difference of potential of 1200 volts between the trolley wire 1 and the ground or relay g.

At z, Fig. 1, is shown a trolley wheel in the act of traversing the contact 5'. In so doing it admits energy from the trolley wire 1 to the signaling system, and simultaneously to the motors M and M', connected in series between the trolley wheel z and the track or earth return g, these motors representing the motors for driving the car or train whose movements are governed by the signaling system. While the motors on the car are thus subjected to 1200 volts pressure the signaling system is subjected only to 600 volts pressure by isolating the signaling system from the ground or rail return of the electric railway system and employing the conductor K insulated from earth and connecting to one terminal of the generator G. Obviously however my invention is equally applicable to an electric railway system employing a voltage other than 1200

volts. And my invention may be applied with advantage to the more ordinary 500 or 600 volt electric railway systems in which case the difference of potential between the conductor 1 and the conductor K may be 70 250 or 300 volts.

It is to be understood also that my invention is not limited to subjecting the signaling system to exactly one-half the voltage of the electric railway system. For example the generator G¹ may produce a pressure of 500 volts, and the generator G a pressure of 100 volts, in which case the signaling system could be subjected to a pressure of only 100 volts.

Fig. 2 illustrates another mode of providing for the signaling system a potential lower than that of the electric railway system. Here G² may be the direct current end of a rotary transformer having the slip rings 60, 61, 62, and 63 connected by taps to suitable portions of the winding of the armature of the machine G². Here the conductors 64 and 65 are those supplying alternating current of one phase to rings 60 and 61, while the conductors 66 and 67 supply alternating current of another phase to the rings 62 and 63, the conversion of the energy taking place in the rotary transformer to direct current form. Between the brushes bearing upon the slip rings 60 and 61 is connected an inductance 68 and between the brushes bearing upon the rings 62 and 63 is connected the inductance 69. The conductor K of the signaling system is connected 100 to the mid-point of each of these inductances. By this means the voltage upon the signaling system will be substantially one-half the voltage of the electric railway system, that is, the voltage of the direct current side of 105 the rotary transformer. Assuming the conductors 64, 65, 66, and 67 omitted and G² to be a direct current generator driven by motor, engine, or otherwise, the slip rings are connected to suitable points of the armature 110 winding and, as in the previous case, the voltage between the conductor 1 and the conductor K will be substantially one-half the voltage maintained by generator G².

In Fig. 3 G³ is a generator supplying current to the electric railway system. Across the terminals of the generator are connected in series the two armatures 70 and 71, and the shunt fields 72 and 73 are also connected in series with each other across the terminals 120 of the generator G³. In this case the conductor K is connected to one terminal of the armature 70, and if the armatures 70 and 71 are similar and disposed in similar fields the voltage of the signaling system will be 125 one-half that of the generator G³. Here again, however, the armature 70, may generate a counter-electro-motive-force different from the armature 71, these armatures running as motor armatures, with the re- 130

sult that the voltage on the signaling system between conductor 1 and conductor K may be made a fraction other than one-half the voltage of the generator G³.

5 In Fig. 4 a plurality of electrolytic cells are connected in series with each other across the terminals of the generator G³, and the conductor K is connected to the midpoint, or any other point, so that the voltage upon the signaling system is less than 10 the voltage of the generator G³. These electrolytic cells 74, 75, may be storage cells, in which case the bank 74 has large enough capacity to carry the current necessary 15 for the signaling system, while the bank 75 may be of smaller cells giving suitable counter-electro-motive-force.

In the different arrangements hereinbefore described, there is disposed between the 20 return conductor of the signaling system and the return conductor of the electric railway system a source of counter-electro-motive-force opposing current flow through the signaling system to the return conductor of 25 the electric railway system, the energy for the signaling system being derived from the source supplying energy to the electric railway system.

Fig. 7 illustrates an arrangement where 30 the energy for the signaling system is independently generated and a source of voltage disposed between the return conductors of the signaling and railway systems. Here G⁶ is the source of energy for the railway 35 systems. Sources 76 and 77 have a total voltage equal to the voltage of the source G⁶. The source 77 opposes current flow through the signaling system to the conductor G of the railway system. The sources 76 and 77 40 may be of any suitable character, as motor or engine driven generators, batteries, etc.

By my system hereinbefore described it is possible to operate a signaling system for an electric railway by energy derived from 45 the same source as that supplying the energy to the electric railway motors, etc., but at a lower potential than the potential of the railway system with the advantages hereinbefore referred to, as reduction in size and 50 cost of the signaling apparatus, less danger of failure of the signaling apparatus, etc.

What I claim is:

1. The combination with an electric railway system, of supply and return conductors 55 therefor, a signaling system, a return conductor for said signaling system independent of the return conductor of said electric railway system, and a source of electro-motive-force connected between said return 60 conductors opposing flow of current through said signaling system to said return conductor of said electric railway system.

2. In combination, an electric railway system, supply and return conductors therefor, means supplying energy to said railway sys-

tem through said conductors, a signaling system, supply and return conductors therefor, the supply conductors of said railway system and of said signaling system being in electrical communication with each other, and 70 a source of electro-motive-force connected between said return conductors opposing flow of current through said signaling system to the return conductor of said railway system.

3. The combination with an electric railway system, of supply and return conductors therefor, a source of energy delivering current over said supply and return conductors for said railway system, a signaling system, and a return conductor therefor in electrical communication with said source of energy and maintained at a potential higher than the potential of said return conductor of said railway system.

4. The combination with an electric railway system, of supply and return conductors therefor, a source of energy delivering current to said system over said conductors, a signaling system having supply and return conductors, and means for impressing upon said conductors of said signaling system energy derived from said source at a potential fractional of the potential of said electric railway system and maintaining said signaling system conductors at a potential higher than the return conductor of said railway system.

5. The combination with an electric railway system, of a contact conductor and a 100 return conductor, a source of energy delivering current to said system over said conductors, a signaling system comprising a signal, signal controlling means and a contact, a second contact movable with a vehicle delivering energy from said contact conductor to said signaling system contact and simultaneously to said vehicle, and a return conductor for said signaling system maintained at a potential higher than the 110 return conductor of said electric railway system.

6. The combination with an electric railway system, of supply and return conductors therefor, a signaling system, a supply conductor therefor in electrical communication with said supply conductor of said railway system, a return conductor for said signaling system independent of the return conductor of said electric railway system, a source of electro-motive-force connected between said return conductors opposing flow of current through said signaling system to said return conductor of said electric railway system, and means common to both said electric railway system and said signaling system for supplying energy thereto.

7. In combination, an electric railway system, supply and return conductors therefor, an associated signaling system, supply 130

and return conductors therefor, said supply conductors being common, and said return conductors maintained at different potentials, whereby said signaling system is subjected to a voltage lower than the voltage of said electric railway system.

In testimony whereof I have hereunto

affixed my signature in the presence of the two subscribing witnesses.
